UNITED STATES PATENT OFFICE.

JOHN DEW, OF CHICAGO, ILLINOIS, ASSIGNOR TO L. S. M. HOOD, TRUSTEE, OF CHICAGO, ILLINOIS.

RAILWAY-CAR.

SPECIFICATION forming part of Letters Patent No. 763,968, dated July 5, 1904.

Application filed July 26, 1901. Renewed January 16, 1904. Serial No. 189,374. (No model.)

To all whom it may concern:

Be it known that I, JOHN DEW, a citizen of the United States, and a resident of Chicago, in the county of Cook and State of Illinois, have invented certain new and useful Improvements in Railway-Cars; and I do hereby declare that the following is a full, clear, and exact description thereof, reference being had to the accompanying drawings, and to the letters of reference marked thereon, which form a part of this specification.

This invention relates to improvements in railway-cars, and more particularly to a railway-car designed for high speed, of light and strong construction, adapted at high speed to be driven by a motor carried thereon. Heretofore many serious obstacles have prevented the attainment of very high speed of a train. One of the most serious difficulties has been the enormous strain upon track construction when trains of great weight are moving rapidly thereon. Another serious difficulty has been the vibration always incident to high speeds and which with the present railway construction are always a source of danger.

The object of my invention is to provide a car much lighter than any heretofore used and supported upon safety-trucks, which permit the car to be positively secured upon the track when in motion and in a manner to prevent derailment, and also to provide means whereby the car when running at a high rate of speed is supported almost wholly from off the truck.

The invention consists of the matters hereinafter described, and more fully pointed out and defined in the appended claims.

In the drawings, Figure 1 is a side elevation of a car embodying my invention. Fig. 2 is a top plan view of the same. Fig. 3 is a slightly-modified form of my invention. Fig. 4 is a top plan view of the same. Fig. 5 is an end elevation of the same. Fig. 6 is a transverse section of the same. Fig. 7 is an end elevation of the form illustrated in Figs. 1 and 2. Fig. 8 is an enlarged detail of the adjusting devices shown in dotted lines in Fig. 3. Fig. 9 is a front elevation of the same. Fig. 10 is a bottom plan view of the same. Figs.

11 and 12 are details of the means for operating the lateral aeroplanes.

As shown in said drawings, A indicates a car-body pointed at each end the more readily to overcome atmospheric resistance and supported at each end on a safety-truck similar to that shown in my prior application for safety-trucks, filed on the 23d day of March, 1901, Serial No. 52,483, and which comprises for each truck a pair of track-wheels B, journaled by means of antifriction-bearings upon a shaft or axle, and a plurality of safety-wheels B', adapted to engage on the under side of a guard rail or rails supported intermediate of the track-rails, as more fully shown in Figs. 5, 6, and 7. Said truck is also provided with means for varying the pressure of the track-wheels on the track.

The car may be constructed of any desired material and in any desired manner, but preferably will be of very light weight as compared with the cars in ordinary use and the weight of its contents or load disposed along a median line, as shown in Fig. 6, (in which a passenger-car is shown,) thereby acting to balance the car equally upon the track-rails. Any desired method of propulsion may be employed, the motor or motors preferably being carried on one or both of the trucks in position to actuate the track-wheels.

For the purpose of entirely or partly supporting the car from off the trucks when under motion and also steadyng the same from vibration due to its motion over slight inequalities in the track aeroplanes C C' are provided on the top and sides of the car, respectively. As shown, the aeroplane C extends longitudinally of and is secured above the car, as shown in Figs. 1 and 7, and approximates in width the width of the car-top and is concave on its under side transversely thereof. Said aeroplane C is so secured to the car as to permit of longitudinal and transverse adjustment. A plurality of rods c are secured at their upper ends along the edges or margins of the aeroplane and extend downwardly along and within the side walls of the car and through air-pressure cylinders c'. A piston-head c' is rigidly secured on each rod within

its cylinder. As shown, pipes c^3 c^4 are connected in each end of the cylinder and may communicate with a source of air-pressure, either a pressure-tank, or an air-pump, or any preferred device, whereby air may be admitted into either end of the cylinder by the operator or motorman, thereby actuating said rods c and moving the aeroplane up or down to the desired adjusted position.

10 For the purpose of more securely holding the aeroplane in its adjusted position a drum c^5 is journaled adjacent to said cylinder, a pinion is rigidly secured axially thereof, and a rack-bar c^6 , rigidly secured on the lower end 15 of each rod c , extends upwardly into operative engagement with said pinion, thereby rotating the drum as the rod is moved up or down in adjusting the aeroplane. As shown, a wire cable passes around said drum and through 20 sheaves located above the same and leads upwardly in close proximity to the corresponding rod c and at the rear thereof and is firmly united to the aeroplane, thereby acting to carry part of the upward strain thereon. A 25 clutch c^7 is provided on each drum-shaft, and a slidable locking-bar c^8 extends longitudinally of the car, and one of the members of each clutch is rigidly secured thereon in position to positively engage its complemental 30 member when moved in one direction and to release the same when moved oppositely. A lever or any desired means may be provided to actuate said shift-bars.

In the construction illustrated in Fig. 7 the 35 aeroplane C is rigidly secured on the car-top and the aeroplanes C' C' are adjustably pivoted on each side of the same and are transversely concave on the under sides thereof. As shown, a casing D , secured longitudinally 40 on each side of the car near the aeroplane C , forms a part of the car-roof and is concave on its outer side to correspond approximately with the curvature of the aeroplane C' and is adapted to contain the same when retracted, 45 as shown in dotted lines. Means are provided for adjusting said aeroplanes outwardly or inwardly comprising an operating-lever d' , rigidly secured upon the shaft d , upon which the aeroplane is pivoted, and which is adapted to 50 be manually engaged by an operator to swing said aeroplanes to their adjusted positions. Any desired means may be used to hold said aeroplanes in their adjusted positions. Conveniently a notched quadrant d^2 is rigidly secured on the car concentric with the shaft d , and a spring-controlled dog d^3 , carried on said lever, normally engages in said notches and acts to hold the shaft from rotation in whatsoever position the aeroplanes may be adjusted. 55 The operation of my device is as follows: Before the car is started the aeroplane C may be adjusted and, if preferred, may be used alone and acts to support a portion of the weight of a car on the atmosphere when the 60 car is in motion. As the motion is acceler-

ated the proportion of weight supported on the aeroplane constantly increases until, if preferred, the greater part of the weight of the car may be supported thereon. If desired, the adjustment may be made while the 70 car is in motion, either to increase or decrease the amount of support afforded by the aeroplanes. If it be desired to increase the lifting power of the aeroplanes, the same may be accomplished by adjustment or by exposing 75 a larger aeroplane-surface upon one side of the car than upon the other—as when, for instance, a strong wind is blowing against one side of the car either or both of the aeroplanes C may be thrown outwardly to a desired position and locked rigidly, as before described. Inasmuch as the car and its contents are supported to a very great extent upon the atmosphere, it is obvious that the vibration due to its motion over the track is minimized, thereby adding greatly to the comfort of the passengers and decreasing liability to accident. Obviously when a car so supported or partly supported on the atmosphere is driven at a 85 high rate of speed it is important to so secure the same upon the track as to preclude the possibility of derailment. For this purpose the guard-wheels B' are secured upon the trucks and engage beneath the guard-rails, thereby preventing the lifting of the truck. 95

As a further improvement a gas-bag G may be employed at the top of the car. As shown, said gas-bag is secured to and beneath said aeroplane C and is of such form that when filled with a gas, such as hydrogen, it will aid 100 materially in supporting the car. Furthermore, when such gas bag or receptacle is used the forward motion of the car and the air-pressure created thereby on the lateral surfaces of the bag act to force a portion of the 105 gas rearwardly of the car, thereby creating a less thickness of the bag at the front end than at the rear, thereby providing an upward curvature on the under and lateral surfaces thereof, which aids in supporting the car. 110

Obviously, if preferred, aeroplanes may be secured rigidly on the sides or top of the car, or the bottom of the car may constitute an aeroplane and the car and its aeroplanes or the method of adjustment thereof may be varied, as preferred, and many details of construction may be varied without departing from the principles of my invention. 115

I claim as my invention—

1. The combination with a car and its trucks, of laterally-adjustable aeroplanes extending longitudinally thereof in the plane of the car and adapted to support the same partly on the atmosphere when in motion. 120

2. The combination with a car and its trucks, of means carried by the trucks acting to hold the car on and to the track and lateral aeroplanes extending longitudinally thereof and adapted to swing outwardly therefrom and acting to partly support the weight of the car 125 130

and its contents from off the truck when in motion.

3. The combination with a car and its trucks and track-wheels of means on the trucks acting to grip the track-wheels to the track-rails and an aeroplane on each side of and extending longitudinally on the car adapted to partly support the weight thereof when in motion.

4. The combination with a car and its trucks and track-wheels of means on the trucks acting to grip the track-wheels to the track-rails and laterally-adjustable aeroplanes extending longitudinally and laterally on the car adapted to partly support the weight thereof when in motion.

5. The combination with a car and its trucks and track-wheels of means on the trucks acting to grip the track-wheels to the track-rails and laterally-adjustable aeroplanes extending longitudinally and laterally on the car near the top thereof adapted to partly support the weight thereof when in motion.

6. The combination with a car and its trucks and track-wheels of means carried by the trucks adapted to grip the track-wheels to the track and laterally-extensible means attached to the car and adapted to partly support the weight of the car when in motion.

7. In a device of the class described, the combination with a car and its trucks and track-wheels, of means for gripping the track-wheels upon the track-rails and a vertically-adjustable aeroplane attached above the car and laterally-adjustable aeroplanes attached laterally of the car and acting to partly support the weight thereof.

8. In a device of the class described the combination with a car and its trucks and track-wheels of means for gripping the track-wheels upon the track-rails and an adjustable aeroplane attached to and extending longitudinally and laterally of the car and adapted partly to support the weight thereof.

9. The combination with a car and its trucks and track-wheels, of means on the trucks for rigidly holding the track-wheels in engagement with the track and pivotally-supported, laterally-curved aeroplanes extending longitudinally of the car and adapted to swing outwardly therefrom.

10. The combination with a car and its trucks and track-wheels of means on the trucks for rigidly holding the track-wheels in engagement with the track and laterally-adjustable and laterally-curved aeroplanes attached to and extending longitudinally of the car.

11. The combination with a car of a plurality of adjustably-secured lateral aeroplanes thereon for partly supporting the same upon the atmosphere when the car is in motion, a track and means for positively securing the moving car on the track.

12. The combination with a track having centrally-located downwardly-facing guard-

rails, car-trucks supported on the track, guard-wheels carried thereby and adjustably engaged beneath the guard-rails, a car pointed at the ends supported on and secured to the trucks and a plurality of lateral aeroplanes pivoted longitudinally of the car and adapted to swing outwardly therefrom whereby the weight of the car upon the trucks is decreased when the car is in motion.

13. The combination with upper and lower oppositely-facing tracks of a car-truck provided with track-wheels adapted to engage on the lower track and guard-wheels adapted for engagement beneath the upper track, a car supported on said truck, an aeroplane secured thereon and approximating the area of the car-top and means for adjusting said aeroplane.

14. The combination with an upper and a lower oppositely-facing track, of a truck provided with track-wheels adapted to oppositely engage said track, a car supported on said truck and aeroplanes pivoted longitudinally of and above said car and on each side of the same adapted to swing vertically therefrom.

15. The combination with an upper and a lower oppositely-facing track, a truck provided with wheels adapted to oppositely engage said tracks, a car supported on said truck and laterally-curved aeroplanes secured above said car and on each side of the same.

16. In a car of the class described, the combination with a rotatively light car-body of means for disposing the weight of the load therein centrally and longitudinally, a compartment on the top of the car extending longitudinally thereof and an adjustable aeroplane in said compartment and means for extending the same laterally of the car.

17. In a car of the class described, a longitudinally-extending transversely-concave aeroplane pivotally secured on each side thereof and a compartment into which said aeroplanes are adapted to be retracted.

18. In a car of the class described, the combination with a shaft extending longitudinally thereof of a transversely-concave aeroplane rigidly secured on said shaft and means whereby the aeroplane may be swung outwardly to a supporting position or inwardly to a concealed position and means for locking the aeroplane when adjusted.

19. In a car of the class described, aeroplanes secured at the top and at the sides thereof, one of said aeroplanes being adjustable and means for adjusting said aeroplane comprising a lever secured to the aeroplane and a notched quadrant adapted to be engaged by a part carried on the said lever.

20. In a car of the class described, the combination with an aeroplane secured at the top thereof of a flexible gas-receptacle secured to the car and adapted to partly support the same when filled with gas.

21. In a car of the class described, the combination with an aeroplane attached to the car

and located above the same of an inflatable receptacle located beneath and in close proximity to the aeroplane and acting together therewith when the car is in motion to partly support the weight thereof.

22. The combination with a vehicle adapted to move on a track of transversely-concaved aeroplanes adjustably secured thereon.

23. The combination with a vehicle adapted to move on a track, of means for holding the same to the track, laterally-adjustable aero-

planes pivoted longitudinally thereof and adapted to swing outwardly therefrom and a vertically-adjustable aeroplane intermediate thereof.

In testimony whereof I have hereunto subscribed my name in the presence of two subscribing witnesses.

JOHN DEW.

In presence of—

L. S. M. HOOD,
LOUIS J. DELSON.
